METALLIC GUARD FOR CONCRETE CURBING AND THE LIKE.

1,086,758.

Specification of Letters Patent.

Patented Feb. 10, 1914.

Application filed July 12, 1910. Serial No. 571,572.

To all whom it may concern:

Be it known that I, CHARLES W. DENNY, citizen of the United States, residing in the city of Philadelphia, State of Pennsylvania, have invented certain new and useful Improvements in Metallic Guards for Concrete Curbing and the like, of which the following is a full, clear, and exact description, reference being had to the accompanying drawings, forming a part of this specification.

My invention relates to metallic protecting guards for rounded corners of concrete curbing, pillars and the like, designed to furnish means to protect from abrasion the rounded edge or corner portion of such concrete structures which is exposed to the destructive impact of wagon wheels and the like.

My improvement in that class of devices has for its several objects to provide a metallic protecting guard which shall, owing to its exterior form, have an increased tendency to convert an impact blow into a sliding contact, and owing to its interior form, including its longitudinal flanges, present means, integral in the device, for not only fully incasing the rounded corner of the concrete curbing, but for inclosing a large portion of the body of the concrete structure and forming an interior locking engagement therewith. My novel guard device, by reason of its flanges, also presents means for operatively assembling therewith a series of anchors of such character as to not only reinforce the whole concrete structure, but furnish reliable aid to reinforce the holding power of both of the longitudinal flanges and also to fixedly interlock both of said elements with each other and with the concrete structure by a body of concrete, forming part thereof, lying between the said elements when operatively assembled; and finally to provide a device, consisting of such elements, capable of such combination with each other and with a concrete curbing, or the like, which may be readily rolled or pressed from sheet metal, and assembled with facility for the purposes and in the manner stated.

To these ends my invention consists of a metallic strip constituting the protector or guard proper, of suitable width, curved in cross-section, approximately a quarter circle

exteriorly, and provided with inturned flanges on each of its opposite longitudinal edges of such relative angularity as to produce an interlocking effect on the underlying body of concrete and on a suitable co-acting anchoring device.

In the preferred form of my device, the guard-strip is rounded in cross-section, of a curvature which is approximately an arc of a circle and of less length than a quarter-circle, with narrow tangentially extended portions on each side, which are straight, and in a plane at right angles to each other, each of the same terminating in an inturned flange approximately at a right angle thereto; also the combination therewith, of a series of anchorage plates, preferably in the form of a loop, but of such character that its terminal ends may engage both of said flanges of the guard strip, and provide therewith an additional inclosing band of metal surrounding a comparatively large body of concrete forming part of the concrete structure, and interlocking said metallic elements to each other and to substantially the entire body of concrete.

In the drawings illustrating my invention: Figure 1 is a sectional view showing my device, in its best form, as applied to a concrete curbing. Fig. 2 is an end elevation, detached, of the metallic guard strip and one of the anchor irons operatively assembled. Fig. 3 is a rear side view of the same. Fig. 4 is an end view of a modified form of the metallic guard-strip, Fig. 5 an elevation, of one of the anchor irons detached, and Fig. 6 illustrates a modified form.

The preferred form of my metallic guard strip is shown in Figs. 1, 2 and 3; while the modified form thereof is shown in end elevation in Fig. 4. Referring first to the former, 2 indicates a vertical cross-section of a portion of a concrete curbing, including its rounded corner 3, a portion of the otherwise usual face of which is supplied by my guard strip. The latter is a rigid strip of metal, preferably iron or steel, molded or rolled, of a thickness which will vary somewhat, but very slightly, according to the service to which it is applied. In practice, for ordinary use, it may be of uniform thickness, but I prefer to make it relatively thicker in its central portion, as at 4, to give it increased stiffness and rigidity, if used

for street curbing where hard usage is common. In respect of that portion of its contact surface, which comprises about the central three-fifths of its width, indicated at 5 in Figs. 1 and 2, it is essentially of a curvature which is approximately circular. If it be made in the modified form shown in Fig. 4 its peripheral width should be substantially a full quarter-circle in cross-section, 10 as indicated at 7, and provided with inwardly-projecting flanges 8-8 of like character on each of its longitudinal edges; these flanges may be at right angles to each other as in preferred form, Figs. 1 and 2, but preferably are bent to form an angle slightly less than would be formed by diametric lines, indicated by the dotted lines in Fig. 4; such construction producing an increased holding effect as hereinafter described.

20 Describing more particularly the preferred form of the guard-strip by reference to Figs. 1 and 2 it will be seen that in the region of the central portion of its peripheral width, which is about three-fifths thereof, indicated at 5, its curvature is substantially that of an arc of a circle, with two narrow longitudinal portions, indicated at 9, 9, these proceeding tangentially from the termini of the central curved portion, in 25 straight lines which are substantially at right angles to each other, and each of the terminal edges thereof provided with an in-turned flange indicated at 8', 8' in Figs. 1 and 2, at right angles substantially, to each other and to the respective flat portions 9, 9, from which they proceed. These flanges are 30 of a depth substantially equal to the width of the flat portions 9, 9, of the body of the metallic strip; but they may be made somewhat deeper if desired, especially if the reinforcing and anchorage irons presently to 35 be described are not used therewith.

40 As a guide to the correct dimensions, it may be stated that the elements shown in 45 the drawings are drawn to a scale from actual constructions which I have applied to use and are of full size for a concrete curb shown at 2 in Fig. 1.

45 It will be seen that the oppositely-disposed flanges on the longitudinal edges of the curved guard strip operate as integral holding or primary anchoring devices therefor, and their position in the concrete, relatively to the curved peripheral surface of the 50 strip is such as to effectually resist any dislodging force applied to either longitudinal edge of the strip, their interlocking and holding force being applied not to the mere surface of the rounded corner of the concrete 55 curb but to a large body thereof lying between such flanges and the inner surface of the strip. In order to reinforce this holding power of the flanged strip, when used for street curbing, I employ a series of anchoring 60 irons, shown in detached side elevation 65

in Fig. 5 and in assembled position in Figs. 2 and 6. These are arranged in series, as illustrated in the rear side view Fig. 3, and each consists of a piece of flat metal, substantially of the width and thickness shown, to accord with the strip element, and bent into loop-form as at 6, preferably a round loop to give more holding surface, and preferably having its extreme terminal ends bent to form lips 6' 6', adapted to rest against and coincide with the inner face of the flanges 8' of Fig. 2 or 8 of Fig. 4, when said elements are operatively assembled as illustrated in Fig. 3; and if properly constructed, as shown and described, said anchoring loops will possess sufficient elasticity to enable the operator to spring them into place in the guard-strip, where they will exert a powerful frictional holding effect on the strip flanges due to such created tension.

70 I prefer the form of guard-strip shown in Figs. 1 to 3, as it gives two narrow flat surfaces coinciding with the flat rise and tread surfaces of the curb, while its curvature is at its central portion only, where the 75 destructive impact blow is most commonly received, and because also it enables me to give the protected concrete a rounded corner of shorter length than when employing the 80 full quarter-circle strip illustrated in Fig. 4.

85 I am aware that it is not new to form a metallic curb-guard with an exterior curved surface and with a single flange, but such a device operates to give only a more or less permanent hold on the concrete structure on 90 one of its longitudinal edges only, and is radically different both structurally and functionally from mine wherein both the opposite longitudinal edges of the curved 95 protector-guard are provided with in-turned flanges, forming a wide and deep curved recess, between them and the interior curved surface of the guard, into which a large portion of the concrete structure enters, the flanges being embedded therein; and the 100 flanges being at an angle to the curved body portion of the guard it is practically impossible to dislodge the same without destroying a large body of the concrete curbing. The flanges may be made deep enough 105 to alone effect a sufficient hold on the concrete, as they lie in relative planes which best resist dislodgment, as shown in Fig. 1; but the holding effect of the flanges will be reinforced by extending their hold through a 110 larger portion of the concrete body, through the medium of the series of anchorage irons 115 constructed as described, and assembled, in the manner stated, with the metallic 120 guard-strip.

125 As usual in forming such concrete structures a moldboard is placed in position to support temporarily the metallic guard-strip and its anchoring irons, the said elements being first assembled as stated, when such 130

anchoring irons are used, and the concrete structure then built up in the usual way, care being taken to force the concrete well into the interior of the curved strip and between its flanges and within the looped anchor-irons; with the result, when my device is employed, as indicated in Fig. 1, that a large body of concrete, forming practically the entire rounded corner of the curb lies between the inner face of the guard-strip and its angular flanges, and is effectually bound thereto against dislodging impact blows, and this effect is aided by the coincidence, in the same plane, of the flat edge portions of the guard-strip with the adjoining flat tread and rise surfaces of the curbing.

I am also aware that anchors and anchoring devices have been used to maintain metallic corner-guards in place on concrete curbing, but all such that I am aware of have been more or less straight rods and the like, connected to the guard-strip and merely embedded lengthwise in the concrete and hence readily pulled out; whereas in my device the anchoring loops, when embedded in the concrete, cannot be pulled out, owing to their form and character without dislodging the great body of concrete between them and the inner face of the guard-strip; and, owing to their relation to both the flanged edges of the guard-strip when the elements are operatively assembled, operate to so firmly hold the guard-strip on the corner of the curbing as to make it impossible to remove it short of destroying the integrity of the whole concrete structure.

Having thus described my invention, I claim as new and desire to secure by Letters Patent:—

1. In a device of the character stated, a metallic guard having a central portion curved in cross-section to approximately a quadrant and which is thicker at the middle than at the edges, adjoining straight portions on opposite sides thereof at right angles to each other, and terminal inturned short flanges thereon substantially at right angles to said straight portions and to each other.

2. In a device of the character stated, a curved metallic guard having inturned flanges on its longitudinal edges, each converging at an angle which would intersect the other, and a series of anchors each bent to bring its terminals within said flanges of the guard and its intermediate portion bowed away from the guard, said anchors being as-

sembled relatively to the guard in spaced relation to each other.

3. In a device of the character stated a curved metallic guard strip having inturned and relatively converging flanges on its longitudinal edges, and a series of metallic anchoring loops each having a spring tension imparted to its terminals and initially engaging said flanges of the guard for support during the placing of the concrete, said loop being spaced from the guard to permit concrete to pass between said elements.

4. In a device of the character stated, a metallic strip curved in cross-section and having an inturned angular flange on each of its longitudinal edges, adapted to form a continuous locking engagement with the concrete, and a series of anchoring loops having terminals sprung between and fixedly engaging both flanges of the guard-strip.

5. In a device of the character recited, the combination with a metallic strip curved in cross-section, and having an inturned flange on each of its longitudinal edges, of a series of loop-shaped anchors with lips at their terminal ends coinciding and forming a locking engagement with both of the oppositely-disposed flanges of the guard-strip.

6. A corner guard for concrete curbing and the like, consisting of a metallic strip curved in cross-section and provided with an inturned angular flange on each of its longitudinal edges, in combination with a series of anchor irons having terminals coinciding with and engaging said flanges respectively and a body portion in the form of a loop projecting inwardly and opposite to the inner face of the guard-strip.

7. In a protected concrete structure having a rounded corner, a metallic strip which is curved in cross-section to coincide substantially with the rounded corner of the concrete structure, said metallic strip having continuous flanges on its longitudinal edges entering the concrete in a direction to interlock with the body portion thereof; and a series of metallic anchor-loops embedded in the concrete, and engaging, by their respective ends, the opposite flanges of said metallic guard-strip.

In testimony whereof, I have hereunto affixed my signature this twenty-fifth day of June, A. D. 1910.

CHARLES W. DENNY.
